(57) **CLAIM**

The ornamental design for a folding bed frame, as shown and described.

DESCRIPTION

FIG. 1 is a top front perspective view of a folding bed frame showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a top front perspective view thereof, shown in an alternate environment of use.

The broken lines shown in the drawings depict portions of the article that form no part of the claimed design.

1 Claim, 6 Drawing Sheets
